METHOD OF DEGREASING

Joseph Savage, Weston Point, Runcorn, England,
assignor to Imperial Chemical Industries Limited,
a corporation of Great Britain

Original application May 5, 1933, Serial No.
669,610. Divided and this application October
7, 1935, Serial No. 43,888. In Great Britain
May 6, 1932

1 Claim. (Cl. 87—6)

This invention relates to an improved method for degreasing by means of volatile solvents such as trichlorethylene. This application is a division of my copending application S. N. 669,610, filed May 5, 1933 now Patent No. 2,020,335 issued Nov. 12, 1935.

A large number of methods and types of apparatus have been proposed for the removal of grease and fat from various types of material, in which 10 cooling surfaces are employed for the cooling and condensation of the vapours of the volatile solvent, the condensate being subsequently returned to the apparatus. In some cases the cooling surfaces are used for cooling a body of liquid solvent 15 or a chamber through which materials to be de-greased are passed before or during treatment.

Experience has shown that these cooling surfaces have a tendency to condense water from the atmosphere in addition to cooling and condensing 20 the solvent. This condensed water then becomes associated with the solvent and thus comes into contact with the metal parts of the apparatus and with the material being treated. This increases the tendency of the metals to corrode and is particularly objectionable in the degreasing of metal 25 goods such as iron or steel.

According to the invention I warm, to a predetermined extent, the cooling water which is used and thereby maintain the cooling and condensing 30 surfaces at a temperature above the dew point of the atmosphere in which the operation is carried out, but substantially below the condensing temperature of the solvent. As a further feature of the invention, the solvent vapours are first 35 brought into contact with the said cooling surfaces and then uncondensed vapours are brought into contact with still cooler surfaces. The condensate from these last surfaces, which may be a mixture of solvent and water, is collected separately from that of the solvent vapour obtained 40 from the first cooling surfaces. Complete condensation is thus effected while at the same time the main bulk of condensate remains uncontaminated by water.

45 In the degreasing of metal goods by means of volatile solvents, the process may be carried out in the vapour phase or in the liquid phase, that is the goods may be exposed to the vapour of a volatile solvent or may be washed by a hot or cold 50 liquid solvent. Combinations of these various methods of working may also be made. The present invention is of course only applicable to processes involving vapour phase degreasing or treatment of the goods with heated liquid solvent.

55 In most forms of apparatus for carrying out

these processes the cooling surfaces consist of pipes through which a supply of cold water flows. In such cases I maintain the desired temperature of the cooling surface by slightly warming the inlet water before admitting to the cooling pipes. 5 This may be done in many ways, for example, by passing the water through a small electrical heater or gas heater, either of which may be conveniently controlled by a thermostatic device. This method is applicable when vapour phase degreasing is 10 used alone or when vapour phase degreasing follows a treatment with cold liquid solvent.

In an alternative method, in processes and apparatus using a degreasing bath of solvent liquor at a raised temperature and with cooling coils arranged above the surface, I pass the cooling water through coils arranged in such a heated bath prior to its passage through said cooling coils. In this case the number of coils immersed in the liquid and the velocity of the cooling water are 15 adjusted so that the desired temperature of the cooling surfaces is obtained. This method may also be applied when the process is a combination of vapour phase and liquid phase degreasing using 20 the liquid at an elevated temperature. 25

An apparatus adapted for carrying out the process, referred to in the preceding paragraph, is illustrated in the accompanying drawing, in which Figure 1 shows an elevation and Figure 2 a plan of the apparatus. Referring to Figure 1, the apparatus comprises an outer casing 1 inside which are located the degreasing chambers 2 and 3 adapted to hold a body of liquid, and separated by the wall 4. Chamber 2 is used for degreasing 30 in the liquid phase and 3 for degreasing in the vapour phase. Both chambers are open to the vapour space 12 in the upper portion of the casing 1. The wall 4 is preferably constructed in the form of a double wall so as to possess an insulating 35 value retarding the transference of heat between the chambers 2 and 3. This enables the temperature of the chamber 2 to be more easily controlled 40 if it is desired to work below the boiling point of the solvent used.

Heating means are provided for each chamber: 45 in the present case the gas burners 5 and 6 are used for this purpose although suitably arranged steam coils or electrical heating devices may be used instead. Waste gases from the burners pass to the outlets 7, 7 by way of the space 8 left between the container 1 and the degreasing chambers 2 and 3. This space, in addition to providing 50 a path for the waste gases, also acts as an insulating jacket for the degreasing chambers and thus obviates excessive loss of heat by radiation. 55

In the base of the degreasing chambers thermos-
5 static devices 8, 8, are provided for the control of
the supply of heat to the degreasing liquid. These
devices control the supply of gas to the burners 5
and 6 and prevent overheating which may occur,
10 for example, when the volatile solvent has become
highly charged with dissolved oils. This control
is of greater importance in the chamber 3 since,
as will be explained below, a supply of boiling
15 solvent is maintained in the base of the chamber
to supply the vapour for the vapour phase de-
greasing. In chamber 2 the thermostat may, if
desired, be used to control the temperature at
some selected point below the boiling-point of the
15 solvent.

Cleaning doors 10 and drain cocks 11 are fitted
to the base of each degreasing chamber. In the
lower portion of each of the degreasing chambers
20 perforated plates 13 are fitted. These plates serve
to carry the goods being treated and must be so
arranged as to permit the total immersion of the
goods in the solvent liquid or vapour, and also in
25 the case of the chamber 3, to prevent contact of
the goods with liquid solvent in the base of the
chamber.

A set of coils 14 is arranged in the upper por-
tion of the chamber 2. The coils are placed
close to the walls of the chamber in order not to
obstruct the passage into and out of the chamber
30 of goods being treated. A suitable connection 15
to the main 21, and provided with a valve 23 is
arranged for the supply of water to the coils and
an outlet pipe 16 connecting through the pipes
25 and 26 to the condensing coils 19, is provided.
35 I also find that it is advantageous to fit a shield
17 for the protection of the coils 14 against dam-
age that might be caused by introducing or with-
drawing the goods.

Towards its upper end the dividing wall 4 is
40 provided with a small overflow outlet 18 leading
from the chamber 2 to chamber 3 to enable excess
liquid in 2 to pass into 3 at a relatively slow rate.
This overflow is placed slightly higher than the
45 coils 14 but at such a distance from the top of
the wall 4 as to avoid a flow of liquid over the top
of the wall into chamber 3 when goods are intro-
duced into the normal volume of liquid in cham-
ber 2.

In the upper portion of the casing 1 at any con-
50 venient height above the wall 4, condensing coils
19 carried by the supports 20 are arranged round
the walls. The supply of water to these coils is
from the coils 14 as previously stated and also
55 from the main 21 through the pipe 22, fitted with
a valve 24, and pipes 25 and 26. At any convenient
point after the junction of the pipes 16 and 22 a
pocket 27 carrying a thermometer is provided for
the observance of the temperature of the water
60 entering the condensing coils. The outlet 28 for
the water from the condensing coils leads to
waste. Below the condensing coils, around the
walls of the casing and adapted to collect the
condensate flowing from the coils and the walls
65 of the casing, is arranged a gutter or channel 29.
Condensed solvent collected by the gutter is de-
livered to the two-way cock 30 whence it flows by
way of pipe 31 back to the chamber 2 or by way
of 32 to a receptacle not shown, for clean con-
70 densed solvent.

70 A suitable cover (not shown) may be provided
for the apparatus to prevent the loss of solvent
by evaporation when the apparatus is not in use.

Prior to the commencement of the degreasing
operation, chamber 2 is charged with the liquid
75 grease solvent, e. g. trichlorethylene, until it com-

mences to flow through the overflow 18. Solvent
is also introduced into the chamber 3, but in this
case the volume must be adjusted so that its
surface is below the perforated plate 13 even
when it is in a state of ebullition. It will be
obvious that this is a necessary precaution if the
efficient degreasing of goods resting on the plate
13 is to be obtained, since after the apparatus has
been in use for some time the solvent becomes
10 charged with dissolved oils and if allowed to con-
tact with the goods will leave a deposit or film of
oil thereon which may not be removed while the
goods are being raised through the vapour prior
to removal from the apparatus.

After charging the apparatus with solvent the 15
temperature of the chamber 2 is raised to the de-
sired figure by means of the gas burner 5 and the
solvent in 3 is heated to boiling to provide for
the vapour phase degreasing. At the same time
the condensing coils 19 are put into operation. 20
The temperature of these coils is adjusted as re-
quired by the invention by suitably proportioning
the feed of water through the coils 14 to the feed
coming directly from the main, the valves 23 and
24 being provided for this purpose. It would of 25
course be possible to maintain the water at the
required temperature by passing the whole sup-
ply through the coils 14 at a suitable rate. Ref-
erence to the atmospheric temperature and hu-
midity will indicate the minimum temperature of 30
the coils 19 for any particular condition.

In the degreasing of metal goods in the appa-
ratus described, they are preferably immersed
first in the chamber 2 in order to remove the bulk
of the oil impurities. Agitation at this stage is
35 also desirable in order that any solid impurities
such as swarf or dust, which may be adhering to
the goods, may be removed by the mechanical
washing action of the liquid. After this exposure
of the liquid, the goods are transferred to the 40
chamber 3 for removal of the residual film of oily
matter which is effected by the condensation
thereon of the solvent. It will, of course, be ob-
vious that when working in this manner the liquid
45 phase degreasing must be carried out at a tem-
perature sufficiently below that at which the sol-
vent boils, in order that the goods may condense
an appreciable amount of solvent when exposed
to the vapour.

Reference has previously been made to the de-
sired temperature in the liquid phase degreasing
chamber 2. When working with trichlorethylene
I have found this to be about 20-30° C. below
the boiling point of the solvent. I have also found
50 that once such a temperature has been attained it
is automatically maintained in this neighborhood
by the condensate from the coils 19 without the
necessity of heating by means of the burner 5.

I claim:

A method of degreasing materials with volatile 60
solvents, which comprises treating the materials
in a solvent vapor bath and limiting the upward
extent of said solvent vapor bath by condensing
the residual vapours by bringing them first into
65 contact with cooling surfaces maintained at a
temperature above the dew point of the atmos-
phere in which the operation is carried out, but
substantially below the condensing temperature
of the solvent, and then into contact with still
70 cooler surfaces, the condensate from these last
surfaces, which may be a mixture of solvent and
water, being collected separately from that of the
solvent vapours obtained from the first cooling
surfaces.
